United States Patent Office

Des. 225,924

Patented Jan. 16, 1973

225,924

CHAIR OR THE LIKE

Stuart John Gilbert and Karen T. Gilbert, Constantine, Mich., assignors to Harter Corporation, Sturgis, Mich.

Filed June 4, 1970, Ser. No. 33,303

Term of patent 14 years

Int. Cl. D6—02

U.S. Cl. D6—75

figure 1

figure 3

FIG. 1 is a rear perspective view of a chair or the like showing our design;

FIG. 2 is a front perspective view thereof; and

FIG. 3 is a side elevational view of another embodiment of a chair or the like of this invention.

We claim:

The ornamental design for a chair or the like, substantially as shown.
